UNITED STATES PATENT OFFICE.

DAVID F. NISBET, OF CRAFTON, PENNSYLVANIA.

FURNACE-RETORT.

1,110,642.

Specification of Letters Patent. Patented Sept. 15, 1914.

Application filed November 17, 1910. Serial No. 592,847.

To all whom it may concern:

Be it known, that I, DAVID F. NISBET, a citizen of the United States, residing at Crafton, in the county of Allegheny and 5 State of Pennsylvania, have invented certain new and useful Improvements in Furnace-Retorts; and I do hereby declare the following to be a full, clear, and exact description of the invention, such as will enable others 10 skilled in the art to which it appertains to make and use the same.

My invention relates to improvements in fuel-consuming furnaces, and is applicable to boiler furnaces, metallurgical furnaces, or 15 any other furnaces using bituminous coal.

My invention is an improvement on the means for burning fuel by a method similar to the one described in previous Letters Patent issued to me, viz., No. 910,305, dated 20 Jan. 19, 1909, and utilizes the same principles of combustion, viz., providing separate air supplies for the combustion of the volatile hydrocarbons and for the combustion of the fixed carbons, but provides a simpler 25 means for supplying air to the fuel, and may be used either alone or in combination with the apparatus described in said previous Letters Patent.

My invention consists in improved means 30 for supplying air to the fuel at the point where the fuel is introduced into the furnace, in quantities sufficient for the complete combustion of the volatile hydrocarbons contained in the fuel, and in means for causing 35 the fuel to pile, or mass, at this point, in such a manner as to compel the complete distillation and combustion of the volatile hydrocarbons, before the fuel is forced onto a grate, and the remaining portion, consisting 40 chiefly of fixed carbon, is burned in the usual manner by either natural or forced draft. This method permits the separate and independent regulation of the air supply for 45 burning the volatile combustibles and the air supply for burning the fixed carbons, effecting perfect combustion with the least possible amount of air, thereby preventing the formation of smoke and securing great economy in the use of fuel.

Referring to the drawings, which show 50 various modifications of my invention, Figure 1 is a horizontal section of one end of a locomotive firebox, showing one form of my invention. Fig. 2 is a sectional side elevation on line a. a. of Fig. 1. Fig. 3 is a

transverse section on line b. b. of Fig. 1. Fig. 4 is an elevation of the installation shown in Figs. 1 and 2. Fig. 5 is a horizontal section of the firebox of a reheating furnace, showing a plunger type of fuel feeding mechanism and twyers for supplying air blast. Fig. 6 is a sectional side elevation on the line a. a. of Fig. 5. Fig. 7 is a horizontal section through the twyers on the line a. a. of Fig. 8. Fig. 8 is a transverse section 65 through the twyers and blast box on the line b. b. of Fig. 7. Fig. 9 is a sectional elevation on the line c. c. of Fig. 8. Fig. 10 is a horizontal section through the firebox of a reheating furnace on the line a. a. of 70 Fig. 11. Fig. 11 is a sectional side elevation of the firebox on the line b. b. of Fig. 10.

Describing the construction and operation of my fuel consuming apparatus: 1 is a hopper, to the lower end of which is affixed an 75 annular casing 2, partly open at the top and communicating with the hopper, and having one end flanged for fastening to the retort 3 and to the mud-ring 4 of the boiler; within the casing, a feeding worm 5 is revolvably 80 mounted on a fixed spindle 6 held firmly in a cover plate 7 bolted to the casing 2. The worm 5 is driven through a worm gear on its outer end by the shaft 8 and worm 9, or other suitable means. The retort 3 is fastened to the mud-ring 4 and may be provided at the lower side with the doors 10, and is supported at its inner side by the rest bar 11. The retort 3 is provided with a detachable 85 edge, or lip, 12, which is preferably divided 90 transversely into two or more sections, and is easily and cheaply replaced. The retort 3 is provided with chambers 13 having detachable caps or twyers 14, through which air is forced from the blast pipes 15. The grates 95 16 are mounted in bars 17 and operated through the rock-shaft 18, levers 19, and links 20 and 21, by any suitable means.

In operating my apparatus, fuel is introduced into the hopper 1 and passes by gravity into the casing 2 and surrounds the revolving worm 5, which forces the fuel into the retort 3. When the fire in the furnace is in full action, the fuel will be massed in front of the feeding mechanism, approximately to the dotted line x. There will be a zone of incandescent fuel approximately from the line y to the line x, through which the hydrocarbon distillates, thoroughly mixed with the air from the twyers, must 105 110

pass, thereby heating the mixture to the point of ignition and burning the mixture of air and gas completely.

Since the complete combustion of the volatile hydrocarbons contained in ordinary bituminous coals requires from 30% to 40% of the total amount of air needed for the complete oxidation of the combustible elements of such coals, it is obvious that means for distilling the hydrocarbons and supplying the distillates with the necessary air in independent and regulatable quantities is essential to their complete combustion to CO_2 . The remaining portion of the fuel, consisting chiefly of coke, or fixed carbon, being continually forced upward by the fresh coal being fed into the bottom of the retort, passes over the edge of the retort onto the grates 16, where it is progressively fed to the other end of the firebox, being burned on the grates in the usual manner.

The type of grates shown in the drawings is the preferable one, and forms the subject matter of a previous application for Letters Patent, but it is obvious that any other form of inclined or feeding grate may be used in connection with my invention.

In another type of installation, 22 is a hopper, affixed to and communicating with the casing 23, which is fastened to the front plate 24 of the furnace, and to which is fastened, at its outer end, the guide 25 for the plunger or pusher 26. In the furnace wall, and running transversely across the furnace, is the blast box 27, communicating through openings in its upper side with the twyers 28, and having a shelf formed by an extension of its upper side and in substantial alinement therewith, extending into the furnace. To the end of this shelf is fastened an upwardly inclined plate, or shelf, 29, the whole forming a retort where the fuel will be massed before passing over the edge of the retort onto the grates 30. Air under pressure is introduced into the blast box 27, whence it passes into the twyers, and through the openings in the inner end of the twyers into the mass of fuel in the retort, mixing with the volatile matter which is being distilled from the fuel in the retort and insuring its complete combustion.

In this type of installation, the fuel is placed in the hoppers 22 and falls by gravity in front of the reciprocating plungers 26, which force it into the furnace through the openings between the twyers 28. The continued operation of the plungers cause the fuel to pile in the retort around and above the twyers, the distillation and combustion of the distilled gasses and the burning of the fixed carbons taking place as hereinbefore described.

Figs. 10 and 11 illustrate another construction embodying the same principles.

The blast box 31 is placed over the openings in the furnace wall through which the fuel is fed, and forms a supporting beam for the superimposed wall. It is provided at its lower side with openings into the twyer boxes 32, which have replaceable caps or twyers 33. The mechanism for feeding the fuel through the openings into the furnace is similar to that shown in Figs. 1 and 2, and the distillation, mixing with air, and combustion of the volatile hydrocarbons and subsequent combustion of fixed carbons occurs as hereinbefore described.

The object of making the fuel feeding apparatus in separate units is twofold,— first, to provide convenient means for feeding the fuel into the furnace between the twyers, and second, to make the apparatus convenient of application to any width of firebox, by using a suitable number of units.

Although the installations illustrated in the drawings are shown as being fitted to the front wall of the furnace, it is obvious that any of them might be fitted to the side walls and feed the fuel toward the longitudinal axis of the furnace, without departing from my invention.

The advantages of my invention are many. It is simple and cheap to construct and efficient and reliable in operation. The twyers being of sufficient size to convey the total amount of air necessary for the complete combustion of the volatile matter contained in the fuel, and the air being supplied at the point where the volatile matter is distilled, the combustion of the volatile matter is quick and complete, giving a hot flame without soot or smoke. When desired, extremely high rates of combustion may be maintained for long periods without decreasing the efficiency or economy, and fires may be banked without danger of the fire working back into the hoppers.

Having described my invention, I claim:

1. In combination with a furnace, a retort extending continuously along the inner side of the front wall of the furnace, comprising a shelf terminating inwardly in an upwardly inclined extension designed to mass the fuel over and around the twyers, means for feeding fuel into the retort at different localities through a plurality of openings in the front wall of the furnace, along the line of the retort, a series of twyers arranged between the fuel feeding devices having their openings below the level of the upper edge of the shelf, and means for admitting air to the twyers in adequate quantity for the proper combustion of the volatile hydrocarbons contained in the fuel.

2. In combination with a furnace, a retort extending continuously along the inner side of the furnace wall and having a shelf terminating inwardly in an upwardly in-

clined extension for the purpose of causing the fuel to mass over and around the twy-
ers, a plurality of twyers spaced along the length of the retort having their openings
5 below the level of the upper edge of the shelf, means for admitting air to the twy-
ers, and means between the spaced twy-
ers for feeding fuel into the retort.

3. In combination with a furnace, a re-
10 tort extending continuously along the inner side of the furnace wall and having a shelf upwardly inclined in the direction of the movement of the fuel so as to cause the fuel to mass over and around twy-
ers, a

plurality of twy-
ers spaced along the length 15
of the retort having their openings below the level of the upper edge of the shelf, means for feeding fuel to the retort through open-
ings between the said twy-
ers, and means for supplying air to the twy-
ers. 20

In testimony whereof, I have signed my name to this specification in the presence of two subscribing witnesses.

DAVID F. NISBET.
